UNITED STATES PATENT OFFICE.

PHILLIP M. McHUGH, OF DENVER, COLORADO.

PROCESS OF RECOVERING SUGAR FROM MOLASSES OBTAINED IN THE MANUFACTURE OF SUGAR FROM SUGAR BEETS.

1,402,079.

Specification of Letters Patent. Patented Jan. 3, 1922.

Application filed January 3, 1919. Serial No. 269,401.

To all whom it may concern:

Be it known that I, PHILLIP M. McHUGH, a citizen of the United States, residing at Denver, in the county of Denver and State 5 of Colorado, have invented certain new and useful Improvements in Processes of Recovering Sugar from Molasses Obtained in the Manufacture of Sugar from Sugar Beets, of which the following is a specification.

10 This invention relates to a process of recovering sugar from molasses obtained in the process of manufacturing sugar from sugar beets.

The recovery process herein referred to 15 is that commonly known as the Steffens House method to recover sugar from the molasses residue of the final crystallization step of the sugar refining process.

It is the object of the present invention to 20 lighten the work required of the filtering devices at present employed in the above-mentioned process to separate the liquor from the hot saccharate which as a precipitate is subsequently added to the material 25 treated in the lime mixers of the sugar refining process of which the molasses is a by-product.

I attain the above-described object by the use of one or more settling devices or gravitational separators commonly known as 30 thickeners in which the solids contained in the pulp settle out of the liquid and are removed through a discharge opening by the action of rotating rakes or scrapers while 35 the liquid rising out of the precipitate is decanted.

Although thickeners of this type may be employed at other points in the process of recovering the sugar, it is of particular value 40 after the heating action by which the sugar remaining in solution is precipitated principally as tri-calcium saccharate, commonly termed hot saccharate.

In the process of recovering sugar from 45 molasses as it is at present performed, filters are employed to separate the liquor from the hot saccharate, and by first permitting the saccharate to settle out of the liquor before it is fed to the filters, a considerable 50 saving in the cost of operating the filters is effected.

This saving of operating expenses relates more particularly to the filter cloths which by reason of the temperature and alkalinity 55 of the hot saccharate mixture, deteriorate

after a short period of use and must be renewed at frequent intervals.

Owing to the comparatively small percentage of moisture contained in a precipitate obtained in the operation of a settling vessel of the character above referred to, pressure filters now generally used for freeing the hot saccharate from liquid, may be eliminated and filtering devices of more simple and economical construction used in 65 the place thereof.

Particularly adapted for use in the process are thickeners of the Dorr type which in their simplest form consist of a settling vessel having an overflow for liquid and an 70 outlet for the discharge of the precipitate which is constantly moved thereto across the bottom of the vessel by the rotary movement of a series of rakes or scrapers on a rotating upright shaft.

While thickeners having a single settling area, may be advantageously employed in the relation to the other steps of the process herein referred to, it is by reason of increased capacity in ratio to floor space and 80 lowered cost of installation and operation, preferable to use thickeners which by a plurality of superposed settling areas are divided into compartments from which the liquid rising out of the solids is automatically decanted. Thickeners of the Dorr type 85 commonly known as "tray thickeners" are particularly adapted for this purpose.

In Figure 1 of the drawings is shown diagrammatically a sequence of steps of the 90 above described recovery process in which the thickening action is included;

Figure 2 shows a sectional elevation in outline of a thickener of the Dorr type here- 95 before referred to, and

Figure 3, represents a sectional elevation of a tray thickener of the same type.

In Figure 2 of the drawings, the reference numeral 5 designates a settling vessel which is preferably of cylindrical form, 6 an overflow launder at the upper edge thereof, 7 an outlet in the central portion of its bottom surface, and 8 the rakes on radial arms of a rotary shaft 9, which continuously move the material settling on the bottom of the vessel 105 toward the outlet.

The tray thickener shown in Figure 3 consists of a tank which by a plurality of superposed decks or partitions 10 is divided into a plurality of settling compartments 12, 110

The material under treatment is fed into the upper compartment; the thickened matter which by the scraping action of the series of rakes 15 on a common arm 14, is continuously moved toward the center of the decks, is discharged through pipes 16; and the clear liquid rising out of the precipitate accumulating on the decks, is decanted by rising in headers 13 to a point of overflow 18 above the upper deck. The decks are provided with central openings 19 through which the material is distributed to the different compartments, and these openings may be surrounded by upstanding collars 20 for the retention of solids until removed through the pipes 16.

Tray thickeners of the same type but operating somewhat differently from that shown in the drawings may be used to advantage. For example, the collars 20 and the discharge-pipes 16 may be eliminated in which case the thickened product is removed from the upper decks through their central openings to collect in the lower compartment from which it is discharged as before.

The Steffens process was devised to recover sugar in molasses residuum from the main beet sugar refining system. The present Steffens process consists of two steps. First, the recovery of sugar by the cold process which has been generally practiced for some time, and is described in Beet Sugar Making and Its Chemical Control, by Y. Nikaido, edition of 1909, pages 249 to 255 inclusive; in Beet Sugar Manufacture by Hall and Rolfe, 2nd edition of 1911, pages 248-251 inclusive; and in Beet Sugar Manufacture and Refining, vol. 2 by Lewis F. Ware, edition of 1907, pages 490-501 inclusive.

The second step of the Steffens process which was developed after the first step had been in operation for some time is described briefly in Beet Sugar Making and Its Chemical Control, supra, page 255, and consists of the so-called Steffens hot process.

Referring to Fig. 1, the molasses from the main sugar refining system is first diluted with water to about 12° Brix and cooled down to about 15° C. (see Beet Sugar Making and Its Chemical Control, supra, page 249). Powdered calcium oxide is gradually added, the temperature being maintained at or slightly below 15° C. Suitable agitation is provided. A slightly greater quantity of calcium oxide is added than is required to precipitate the sugar present as tricalcium saccharate. The latter compound is insoluble, and when the above described action is complete the filtered liquid will show about 6.5° Brix (see Beet Sugar Making and Its Chemical Control, supra, page 249). The mixture is next filtered for the recovery of the insoluble trisaccharate, which is finally washed with cold water while in the filter

presses. The filtrate from this operation was formerly considered waste water and discarded, but with the institution of the Steffens hot process it is now further treated as indicated in Fig. 1. My invention relates to this so-called hot process.

The above mentioned filtrate from the so-called cold process is heated to about the boiling point, or as more recent practice has indicated, to about 85° C. Practically all of the remaining sugar in the liquid which is probably in the form of mono-calcium saccharate (see Sugar Making and Its Chemical Control, supra, page 255) is now precipitated as the insoluble tri-calcium saccharate. According to my process the mixture of waste liquor, now practically free of sugar and solution, and the precipitated tri-calcium saccharate, is removed from the heater to a gravitational separator or thickener, such, for example, as a Dorr thickener, where the tri-calcium saccharate is settled out as a thick sludge, and the waste water, practically free of sugar, is overflowed to waste. The discharge of the thickener containing the tri-saccharate with a comparatively small amount of waste water is now introduced into suitable filters, preferably continuous rotary suction filters, where the precipitate of the tri-calcium saccharate is further de-watered and washed with hot water.

The washed precipitate, representing the so-called hot saccharate, is now combined with the cold saccharate from the preceding step, and returned to a point near the head of the main system for the recovery of sugar from beets.

The so-called cold saccharate described above, is according to Beet Sugar Making and Its Chemical Control, supra, page 251, composed principally of di- and tri-calcium saccharate. The so-called hot saccharate described above is according to the same reference, page 255, composed principally of tri-calcium saccharate.

By employing a thickener as above described to separate the sludge from the liquid in the so-called Steffens hot process, I have effected an important improvement therein, and have considerably lessened the operating expenses which are incident upon the use of filter presses now commonly employed at this stage in the process of beet sugar manufacture. The elimination of pressure filters also results in a saving in labor, and a decrease in the percentage of sugar carried away in the solution in the effluent.

Having thus described my invention what I claim and desire to secure by Letters-Patent is:

1. In a process of recovering sugar from molasses obtained in the manufacture of sugar from sugar beets, the method of sepa-

rating calcium saccharate from a liquid in intermixture therewith, which comprises continuously introducing the liquid mixture into a container, allowing the solids to settle 5 out of the liquid, continuously overflowing the clear liquid from the upper part of the container, continuously removing the precipitate to a point of discharge by means of a rotating scraper, and filtering the precipitate.

2. In a process of recovering sugar from molasses obtained in the manufacture of sugar beets, the method of separating hot saccharate from a liquid in intermixture 15 therewith, which comprises continuously introducing the liquid mixture into a container, allowing the solids to settle out of the liquid, overflowing the clear liquid from the upper part of the container and continuously removing the precipitate to a central point of discharge by the movement of a series of scrapers mounted upon rotating arms radiating from the point of discharge, and filtering the precipitate.

25 3. The process of recovering sugar from molasses obtained in the manufacture of sugar from sugar beets, which comprises mixing the molasses with lime, cooling the

mixture, filtering it, heating the filtrate to precipitate saccharate, continuously introducing the resulting mixture of solids and liquid into a container, allowing the solids to settle out of the liquid, continuously overflowing the clear liquid from the upper part of the container, continuously removing the precipitate to a point of discharge by a continuous rotary movement of radially disposed scrapers, and filtering the precipitate.

4. The process of recovering sugar from molasses obtained in the manufacture of sugar from sugar beets, which comprises mixing the molasses with lime, cooling the mixture, filtering it, heating the filtrate to precipitate saccharate, introducing the resulting mixture of solids and liquid into a tank divided into a plurality of superimposed compartments, allowing the solids to settle out of the liquid into the compartments, continuously overflowing the clear liquid from the upper part of each compartment, continuously removing the precipitate to a central point of discharge by means of rotary scrapers, and filtering the precipitate.

In testimony whereof I have affixed my signature.

PHILLIP M. McHUGH.
